FRANÇOIS BAVEREY, OF OULLINS, FRANCE, ASSIGNOR TO SOCIÉTÉ DU CARBURATEUR ZENITH, OF LYON, FRANCE.

CARBURETER FOR INTERNAL-COMBUSTION ENGINES.

1,089,372.

Specification of Letters Patent.

Patented Mar. 3, 1914.

Application filed September 17, 1912. Serial No. 720,822.

To all whom it may concern:

Be it known that I, FRANÇOIS BAVEREY, a citizen of the French Republic, residing at Oullins, in France, have invented certain new and useful Improvements in Carbureters for Internal-Combustion Engines, of which the following is a specification.

This invention relates to improvements in carbureters of the kind provided with a principal jet for the feed of fuel in the usual manner, and an auxiliary fuel jet operating during starting of the motor and slow running thereof.

The present invention provides an improved arrangement of the auxiliary jet tube and improved means for feeding the chamber in which the auxiliary jet sucks.

The auxiliary jet orifice is arranged to issue into the suction conduit at a point opposite the edge of the throttle valve regulating the suction in such a way that when said valve is closed its edge completely closes the auxiliary jet orifice.

The annexed drawing illustrates the invention and shows the carbureter in section.

The auxiliary jet orifice *a* of relatively large section issues into the suction conduit *h* at a point opposite the edge *c'* of the throttle valve *c* as shown in the drawing, so that it is completely obturated by the edge or surface *c'* when the valve *c* is closed and is progressively uncovered as the throttle valve is opened. The sectional area of the orifice *a* thus increases from the start of the action of the carbureter during the period when practically no fuel is fed by the ordinary jet *d*. The sectional area of the orifice *a* becomes constant when the throttle valve is sufficiently open to fully uncover same, the suction then becoming sufficient to put the principal jet *d* in action.

The auxiliary jet sucks through a tube *f* from a chamber *b* fed with fuel through a calibrated orifice *o* forming a communication with the constant level vessel *i*. The chamber *b* is preferably arranged in a well which communicates with the float chamber as such construction facilitates the mounting of the chamber and also serves to keep more steady the level of the liquid immediately surrounding the chamber.

If the chamber *b* were freely open to atmospheric pressure the orifice *o* being under constant pressure would have a constant feed, independently of the suction of

the motor. If on the contrary the chamber *b* were completely closed the feed of the orifice *o* would be proportional to the suction. It is between these two extremes that the auxiliary jet is caused to operate in the present invention. For this purpose the chamber *b* communicates with the atmosphere through orifice *e'* by one or more small orifices *e* the size of which is selected so as to maintain reduced atmospheric pressure in the chamber *b*, above which the suction of the suction conduit commences to become effective in said chamber and increases the feed of the orifice *o*. By suitably selecting the respective sizes of the orifices *a e o* by calculation or by experiment the carburation can be regulated in a permanent manner for any type of motor; the feed of the orifice *o* can nevertheless be varied within certain limits by adjusting the height of the orifice *o* by adjusting the tube *f* and chamber *b* relatively to the sleeve *g* upon which sleeve the tube and chamber are frictionally supported.

It has been found by trial that carbureters provided with orifices of the dimensions set forth in the following table have given very good results:

	Diameter of orifices.		
	<i>o.</i>	<i>e.</i>	<i>a.</i>
1st carbureter	0.3 mm.	0.5 mm.	2.5 mm.
2nd carbureter	0.4 mm.	0.8 mm.	3.0 mm.
3rd carbureter	0.6 mm.	1.2 mm.	3.5 mm.
4th carbureter	1.0 mm.	1.4 mm.	4.0 mm.

In each case the orifice *e'* should be just large enough to maintain the atmospheric pressure around the tube *b*.

The above dimensions are for carbureters, the diameter of the outlet pipe of which may vary from 20 mm. to 60 mm. It is of course understood that in each instance there may be but one orifice *e* having the necessary area or there may be a number of orifices whose total area is equal to the necessary area.

What I claim as my invention and desire to secure by Letters Patent of the United States is:

1. A carbureter for explosion motors comprising in combination a principal fuel jet, an auxiliary fuel tube having a feed orifice issuing into the motor suction conduit at a

- point opposite the edge of the throttle valve of said conduit when said valve is closed, an auxiliary fuel container having means for the supply of fuel thereto, and means for maintaining atmospheric pressure therein, and a tube adjustable as regards its height within said auxiliary fuel container, in which said auxiliary fuel tube sucks, said adjustable tube being provided with a calibrated orifice for the feed of fuel from said auxiliary fuel container therein and having air inlet orifices in its walls communicating with said auxiliary container, said orifices being of a size to produce reduced atmospheric pressure in said adjustable tube.
2. A carbureter for explosion motors comprising in combination a principal fuel jet, an auxiliary fuel tube having a feed orifice issuing into the motor suction conduit at a point opposite the edge of the throttle valve

of said conduit when said valve is closed, an auxiliary fuel container having means for the supply of fuel thereto, and means for maintaining atmospheric pressure therein, and a tube within said auxiliary fuel container, in which said auxiliary fuel tube sucks, said tube being provided with a calibrated orifice for the feed of fuel from said auxiliary fuel container therein and having air inlet orifices in its walls communicating with said auxiliary container, said orifices being of a size to produce reduced atmospheric pressure in said tube. 25

In witness whereof I have signed this specification in the presence of two witnesses. 35

FRANÇOIS BAVEREY.
